(57) **CLAIM**

We claim the ornamental design for a stimulator assembly, as shown and described.

DESCRIPTION

FIG. 1 is a top perspective view of a stimulator assembly, showing our new design;

FIG. 2 is a bottom perspective view of the stimulator assembly of FIG. 1;

FIG. 3 is a front view of the stimulator assembly of FIG. 1;

FIG. 4 is a rear view of the stimulator assembly of FIG. 1;

FIG. 5 is a top view of the stimulator assembly of FIG. 1;

FIG. 6 is a bottom view of the stimulator assembly of FIG. 1;

FIG. 7 is a right view of the stimulator assembly of FIG. 1;

FIG. 8 is a left view of the stimulator assembly of FIG. 1;

FIG. 9 is a top perspective view of a first component of the stimulator assembly of FIG. 1;

FIG. 10 is a bottom perspective view of the component of FIG. 9;

FIG. 11 is a front view of the component of FIG. 9;

FIG. 12 is a rear view of the component of FIG. 9;

FIG. 13 is a top view of the component of FIG. 9;

FIG. 14 is a bottom view of the component of FIG. 9;

FIG. 15 is a right view of the component of FIG. 9;

FIG. 16 is a left view of the component of FIG. 9;

FIG. 17 is a top perspective view of a second component of the stimulator assembly of FIG. 1;

FIG. 18 is a bottom perspective view of the component of FIG. 17;

FIG. 19 is a front view of the component of FIG. 17;

FIG. 20 is a rear view of the component of FIG. 17;

FIG. 21 is a top view of the component of FIG. 17;

FIG. 22 is a bottom view of the component of FIG. 17;

FIG. 23 is a right view of the component of FIG. 17;

FIG. 24 is a left view of the component of FIG. 17;

FIG. 25 is an exploded top perspective view of the first and second components comprising the stimulator assembly of FIG. 1; and,

FIG. 26 is an exploded bottom perspective view of the first and second components comprising the stimulator assembly of FIG. 1.

The broken lines in the drawings depict portions of the stimulator assembly that form no part of the claimed design.
